CENTRALIZED TRAFFIC CONTROLLING SYSTEM

Neil D. Preston, Rochester, N. Y., assignor to
 General Railway Signal Company, Rochester,
 N. Y.

Application January 30, 1931, Serial No. 512,257

33 Claims. (Cl. 246—3)

This invention relates to systems for governing traffic on railroads, and more particularly to systems known as centralized traffic control systems.

5 In a centralized traffic control system of the type contemplated by this invention, the switches and signals at various points along a railroad track, throughout an extended territory, are placed under the control of an operator in a central control office, in such a way that the operator may at will change the position of the switches, subject to automatic approach and detector locking control circuits, which prevents unsafe operation of any switch, and may also 10 hold at stop any of the signals, or allow them to clear, dependent upon the position of the associated switches, and also provided the location of trains makes it safe for such a signal to indicate proceed. In such a type system, it is desirable 15 that the operator be fully and accurately informed of the movement of trains, and also of the operation of the switches and signals which he controls, in order that he may direct train movements most efficiently. For this purpose, 20 various indications should be transmitted to the control office to show, among other things, the presence or absence of a train on a particular section of track, the over and locked position of a switch, and the clear or stop indications of a 25 signal.

In accordance with this invention, the indications of the condition of a switch and the indications displayed by its associated signals are transmitted to the control office in the same way 30 as heretofore employed in systems of this type; but instead of displaying these indications separately, so that the operator has to make a mental summation of these indications, so to speak, in order to determine if this switch and its signals have been operated as he desired, it is proposed to provide "route" and "no route" indicating lamps, or equivalent means, and a movable miniature switch point, or the like, indicating the position of the switch. These indicating 35 means or devices are jointly controlled by indications received from the field and by the position of the switch and signal control levers, in such a way that the operator can easily and quickly tell if a route for train movement has 40 actually been set up in the field and the signal cleared, the direction in which trains have been signalled to move over the switch, the position of the switch, and such other information as the operator needs to guide him in the manipulation of the control levers.

Stated more specifically, in accordance with this invention, a "route" lamp indicating direction by an arrow, or the like, and located adjacent each switch on the track diagram of the railroad under the operator's supervision, is 5 lighted on the control board before the operator, when that track switch is over and locked in a position corresponding with the position of the switch control lever, and when a signal in the field has actually been cleared for trains to move 10 in the direction indicated by this lamp. Thus, when such a "route" lamp is lighted, the operator knows that the switch and its associated signals in the field have properly responded to the control he has established by positioning the 15 control levers, and that a route for trains has actually been set up over the switch in the normal or reverse position indicated by the miniature switch point, and in the direction indicated by the route lamp lighted. If a route lamp adjacent the switch is not lighted for either direction, the operator knows that no route has been 20 set up for trains to move over that switch, and that further manipulation of the control levers may be necessary to set up this route. The "no 25 route" indication is displayed when, and so long as, the corresponding switch and its signals in the field are out of correspondence with the positions of their control levers. This "no route" indication is displayed whenever the operator 30 moves either the switch or the signal control lever to a position out of correspondence with the corresponding switch and signals in the field, and is maintained displayed until said switch and signals have operated to the desired positions. 35 If this "no route" indication is displayed for a time longer than that required for the switch and signals to operate, then the operator knows that these devices in the field have not properly operated for some reason, and that further action 40 may be necessary to permit trains to move. Such a "no route" indication makes it necessary for the operator to watch for changes in the standing indications of the position of a switch and the indications of signals, now ordinarily 45 used, in order to determine if the system has operated as desired.

According to this invention, the indications of the presence of trains in various track sections are displayed in the usual way by light- 50 small indicating lamps on the track diagram; but provision is also made for controlling the lighting of these lamps in such a way that each new indication may be readily identified by the operator, and will remain displayed, irrespec- 55

tive of the continued presence of the train, until 5 recognized by the operator. Stated more specifically, when a train enters a track section, the corresponding indicating lamp is flashed intermittently, thereby distinguishing it from other 10 indications of track section occupancy which may have been standing for some time; and this 15 flashing of the light continues, until the operator manipulates a push button, or equivalent means, 20 as an act of recognition of this new indication of a train movement.

Another feature of this invention relates to 25 means for improving the operation of selective type communication systems by suppressing or holding back initiation of the operation of the 30 system to transmit indications from a particular field station, upon change in the condition of a switch or its associated signals at that station, until all of the conditioned operations of the 35 switch and signals have taken place, so that all indications of the new conditions may be transmitted to the control office during one operating cycle. In connection with this feature of the 40 invention, it is assumed that indications of the locked or unlocked condition of the switch, or its 45 over and locked position, and of the clearing or putting to stop of a signal, are all to be transmitted to the control office. In such a case, since the operation of the switch and its associated 50 signals take place successively, with operating times between the successive operations, these 55 separate indications would ordinarily be transmitted to the control office one at a time during separate operating cycles; and several 60 operations of the system would be necessary to transmit to the control office a number of indications which are of no interest to the operator until all have been received. This indication 65 suppression feature of this invention reduces the number of operating cycles required, upon 70 change in a route at a station, to transmit to the control office the necessary indications from that station, thereby avoiding any objectionable 75 delay in the transmission of indications from other stations.

This invention also embodies means for transmitting, during different operating cycles, either 50 one of two groups of indications, according to the changes that may have taken place to necessitate 55 transmission of a new indication in one group or the other. More specifically, it is proposed to transmit during one operating cycle the 60 indications of the operated condition of a switch and its associated signals as one group, and the 65 indications of the presence of a train on certain track sections as another group. In this way, the 70 number of indications to be transmitted on one operating cycle is reduced and is more nearly in accord with the number of controls 75 which have to be transmitted for the control of a switch and its associated signals. In other words, by transmitting the indications in groups as proposed in accordance with this invention, the 80 number of steps in an operating cycle is made substantially the same for both controls and indications.

These characteristic features of the invention, thus briefly stated, will be explained more in detail in the following description of one embodiment of the invention; and various other characteristic features, functions and advantages of a system embodying this invention will in part be pointed out, and in part apparent as the description progresses.

75 In the accompanying drawings, the invention

has been shown applied to one switch and its associated signals, such as used at one end of a passing siding; but it should be understood that the invention is not limited, as thus shown, to the control of one switch and its signals, but may be extended for any desired number of switches and signals, and may be readily applied to all types of track layouts.

5 In describing the invention in detail, reference will be made to the accompanying drawings, in 10 which similar parts throughout the several views are designated by similar reference characters provided with distinctive exponents, and in which:

15 Fig. 1 illustrates the apparatus and circuit arrangements provided for a typical control office having indication means constructed and arranged according to the present invention.

20 Fig. 2 illustrates the apparatus and circuit arrangements employed at a typical field station 25 for providing the information of the traffic governing conditions at a single track switch in accordance with the present invention, and adapted to be associated with the apparatus employed in the control office.

25 Fig. 3 illustrates the apparatus and circuit arrangements employed in the system for starting it into operation at a field station. The relays and contacts of this figure correspond to the relays and contacts of Fig. 3 of the Patent No. 30 2,129,183 dated September 6, 1938 granted to N. D. Preston et al.

30 Fig. 4 illustrates the line circuit organization connecting the control office and the several field stations and corresponds to the above-mentioned 35 Patent No. 2,129,183.

40 Fig. 5 illustrates the stepping relay bank proposed to be employed with the system of the present invention, which Fig. 5 corresponds to Fig. 5 of the above-mentioned Patent No. 2,129,- 45 183.

45 Fig. 6 is an illustration of the circuit arrangement for transmitting controls over the line circuit illustrated in Fig. 4, and these circuits are taken from the above-mentioned Patent No. 2,129,183.

50 For the purpose of simplifying the illustration and facilitating in the explanation, the various parts and circuits constituting the embodiment of the invention have been shown diagrammatically and certain conventional illustrations have been employed, the drawings having been made more with the purpose of making it easy to understand the principles and mode of operation, than with the idea of illustrating the specific construction and arrangement of parts that would be employed in practice. Thus, the various relays and their contacts are illustrated in a conventional manner, and symbols are used to indicate connections to the terminals of batteries or other sources of electric current, instead of showing all of the wiring connections to these terminals. The symbols (+) and (-) are employed to indicate the positive and negative terminals respectively of suitable batteries or 60 other sources of direct current; and the circuits with which these symbols are used, always have current flowing in the same direction. The symbols (B+) and (B-) indicate connections to the 65 opposite terminals of suitable batteries or other direct current source which has a central or intermediate tap designated (CN); and the circuits with which these symbols are used, may have current flowing in one direction or the other depending upon the particular terminal 70 75 80 85 90 95 98 99

used in combination with the intermediate tap (CN).

While certain features of the invention are applicable to, and useable with, any type of communication system for centralized traffic control, whether obtained by direct line wire control or by some form of a selective type communication system, the specific embodiment of the invention illustrated has been shown in a form adapted for use with a selective communication system of the duplex coded type, shown and described in detail in the prior patent to N. D. Preston et al., Patent No. 2,129,183, dated September 6, 1938. Thus, before considering the structure and mode of operation of the parts constituting this invention, it becomes necessary to explain some of the features of this particular duplex coded type of communication system, insofar as material to an understanding of the present invention, reference being made to said prior application for other details of the structure and operation of such a duplex coded communication system not directly related to the features of this invention.

Communication part of the system.—The communication part of the centralized traffic control system comprises a transmitting and receiving equipment located in the control office and interconnected with transmitting and receiving equipments located at the various field stations. For example, a control office transmitting and receiving equipment has been indicated as included within a dotted rectangle 10 of Fig. 1, and a field station transmitting and receiving equipment has been indicated as included within a dotted rectangle 11 of Fig. 2, with these equipments showing only those parts which are directly related to the devices and functioning of the particular embodiment of the present invention.

Fig. 3 illustrates the arrangement proposed for starting the system into operation from a field station. The relays and contacts of this figure illustrate corresponding relays and contacts of Fig. 3 of the above-mentioned Patent No. 2,129,183, with the preceding numeral 3 added to the corresponding reference characters. Relay 3GS is relay GS of Fig. 2 of the present application and contact 321 is contact 21 of Fig. 2 of the present application. It will thus be obvious that the energization of either relay CH or GS of Fig. 50 will complete a circuit for picking up relay 3P¹ of Fig. 3, which in turn de-energizes the message line for dropping relay 4M⁰ of Fig. 4 which starts the system into operation in any approved manner, such for example as illustrated by relay M⁰ of Fig. 1B of the above-mentioned Patent No. 2,129,183.

Fig. 4 illustrates the line circuit organization proposed, which figure corresponds to Fig. 4 of the above-mentioned Patent No. 2,129,183. Corresponding reference characters have been used, with the addition of the prefix 4 in the present drawings. The operation of this line circuit for impulsing, transmitting controls and indications, selection of stations and the registration of stations is explained in detail in the above-mentioned Patent No. 2,129,183.

Fig. 5 illustrates the stepping relay bank proposed to be used in the system of the present invention, which figure corresponds to Fig. 5 of the above-mentioned Patent No. 2,129,183. The relays and contacts have been given reference characters which correspond to Fig. 5 of the Patent No. 2,129,183, but with the preceding numeral 5 added. The operation of this stepping bank is explained in detail in the above-mentioned Pat-

ent No. 2,129,183. The stepping bank at the station operates in a manner similar to that in the office and consequently it is not believed necessary to show the circuits of the field station stepping bank in detail. The numbers 1, 2, 3 and 4 appearing within the blocks which illustrate the stepping relays in Figs. 3 and 5 indicate the first, second, third and fourth stepping relays respectively. While the circuits illustrated in Fig. 5 show the operation of the first four stepping relays only, it will be understood that the remaining relays of the bank, such as 5, 6, 7 and 8 of Fig. 2 and e, f, g, and h of Fig. 1, operate in response to additional steps of the cycle in the same manner as those illustrated.

Fig. 6 is a diagrammatic illustration of the proposed arrangement for transmitting controls over the stepping and control line in accordance with the polarity of the impulses applied to this line as selected, for example, by the position of lever 6SML which corresponds to lever SML of Fig. 1 of the present application and lever SML of Fig. 1A of the above-mentioned Patent No. 2,129,183. The relays and contacts of Fig. 6 illustrate corresponding relays and contacts of Fig. 2, Fig. 1A, Fig. 1B and Fig. 2 of the Patent No. 2,129,183, with the preceding numeral 6 added to the corresponding reference characters. Reference may be made to the above-mentioned Patent No. 2,129,183 for a detailed explanation of the control transmission operation illustrated in Fig. 6.

In this duplex coded type of communication system, three line wires connect the control office with the several field stations forming a series stepping and control circuit, and a series message circuit, with a common return connection. In the accompanying drawings these three line wires are designated 12, 13 and 14. The transmission of controls from the control office to one selected station, and/or the transmission of new indications, if any, from that station or some other station, back to the control office, takes place simultaneously during the execution periods of a predetermined number of steps resulting from the successive energizations of the stepping circuit at time-spaced intervals, this being conveniently termed an operating cycle. In the beginning of such an operating cycle, a slow-acting relay SL⁰ in the control office (see Fig. 1) and a similar relay SL at each field station (see Fig. 2) are energized, and maintained energized throughout the operating cycle. The application of the successive impulses of the cycle to the stepping circuit causes the operation of the stepping relays at the control office and at each field station, one step for each impulse. The time periods or spaces between the successive impulses of a cycle are conveniently termed execution periods during which periods the controls and indications can be suitably transmitted or executed. These execution periods are marked off by a quick acting relay LR⁰ in the control office (see Fig. 1), and a quick acting relay LR (not shown) at each field station.

The system is normally at rest, but is set into operation by the operator to establish communication with a selected station by actuation of a starting button SB (see Fig. 1) associated with the control levers for that station. The system may also be set into operation independently of the operator, whenever a change takes place at any one of the field stations requiring the transmission of indications. Referring to Fig. 2, the system is thus set into operation, whenever the change relay CH, or the group selecting relay GS, 75

are energized to close their contacts 20 and 21. The detail apparatus and circuits for initiating operation of the system upon actuation of a starting button SB for a station, or upon energization of the relay CH or GS at a field station, are disclosed in the application of N. D. Preston et al., above-mentioned, and since it is sufficient for an explanation of the present invention to understand that such operation takes place, no attempt has been made to illustrate or describe such detail circuits and apparatus.

The operating cycle of this duplex coded communication system consists of a station selecting part and a transmitting part. During the station selecting part of the operating cycle, the station to receive controls from the control office is selected in the manner explained in detail in said application of Preston et al., above mentioned, resulting in the energization of the relays SO and 20 TR shown in Fig. 2, which are at that station. Also, during this station selecting part of the operating cycle, one of the several field stations having new indications to transmit is registered in the control office, this condition being manifested by the energization of a station registering relay in the control office, such relay as C³ (see Fig. 1), and the energization of the relays SI and TR at the corresponding field station, such for example as shown in Fig. 2. During the 25 transmitting part of the operating cycle, a series of stepping relays in the control office, such as the relays d, e, f, g and h (see Fig. 1), and a similar series of stepping relays at the station selected for outgoing controls and/or at the station registered in the control office for incoming indications, such as the relays 4, 5, 6, 7 and 8 (see Fig. 2), are energized sequentially one at a time in synchronism by impulses applied to the stepping circuit; and on each of these successive 30 steps either one of two distinctive controls, or two distinctive indications, may be simultaneously transmitted from or to the control office, all in a manner fully explained in said application of Preston et al., above-mentioned.

For the purpose of understanding the present invention, it is not necessary to explain in detail how these controls are transmitted in this duplex coded type of communication system; and it is sufficient to note that such transmission of either 45 one of two controls on each step results in positioning the contact finger of a polar relay in one extreme position or the other, in correspondence with the position of the corresponding control lever. Each of these polar function control relays 50 at a field station is of the dead-beat or magnetic stick type, so that its contact fingers are held, in the position to which they were last operated, by a permanent magnet or equivalent means until they are operated to the other position.

In a similar way, the transmission of one of 60 two indications on each step results in positioning the contact finger of a magnetic stick polar relay in the control office to one extreme position or the other, in accordance with the position or condition of the corresponding device being indicated. In this transmission of indications from the several field stations, in addition to the registration of these stations in the control office one at a time by the energization of a corresponding 65 station registering relay, such as the relay C³ shown in Fig. 1, and the energization of the relays SI and TR at the particular station thus registered, there is also, in accordance with this invention, a selection of the group of indications 70 to be transmitted on the particular operating

cycle then in effect; and for this purpose there is a group selecting relay GS⁰ in the control office for each station, and a group selecting relay GS at each field station. Typical examples of the transmission of indications will be explained more 75 in detail hereinafter.

Keeping in mind this general organization of the complete communication system contemplated in connection with the particular embodiment of the invention illustrated, and particularly the fact that controls and indications may be transmitted to and from any one of several field stations, one at a time, during successive operating cycles, consideration may now be given to an explanation of the present invention as if 10 it were applied to any one station, as shown in the accompanying drawings.

Control office equipment.—The control office (see Fig. 1) includes besides a transmitting and receiving equipment, a control machine having 15 a group of control levers for each field station, a miniature track layout corresponding in every way to the actual track layout in the field, and various indicating lamps or equivalent devices, together with apparatus and circuits to accomplish 20 proper functioning of the system. Fig. 1 illustrates diagrammatically a portion of such a control machine for one track switch, cross-over, or the like.

This apparatus for one track switch at a field 30 station comprises a switch machine control lever SML, a signal control lever SGL, a starting button SB, and a cancelling key CK.

The movement of the lever SML to one extreme 35 position or the other results in the normal or reverse control of the corresponding switch at the corresponding field station, through the medium of the communication system; and the movement of signal control lever SGL from the intermediate or vertical position shown, corresponding to signals "at stop", to the right or left 40 clears the signals over the switch in an east or west direction respectively. The starting button SB, when momentarily actuated by the operator, results in the initiation of the communication 45 system into operation for the transmission of the controls associated with that station, as set up by the levers SML and SGL.

A miniature track diagram corresponding with 50 the actual track layout in the territory under the supervision of the operator, is preferably made a part of the control machine, and positioned adjacent the control levers for the several field stations. As representative of such a track diagram, (see Fig. 1) a portion of track together with one pivoted miniature track switch point ts is shown to represent the actual track and track switch TS located at the field station shown in Fig. 2. The position of the track switch TS is indicated upon the track diagram by the movement of the miniature switch point member ts to normal or reverse positions, as operated by electro-magnetic means hereinafter pointed out.

The presence of a train on different portions 60 of the track adjacent the switch is preferably indicated by small lamps of the telephone switch-board type, located on the track diagram, these lamps being lighted when a train is present on the corresponding track section. As illustrated in Fig. 1, a lamp OSL is lighted to indicate the 65 presence of a train on the usual detector track circuit associated with the switch, lamps EAL and WAL are lighted to show the presence of a train approaching the switch from the east and west 70 respectively, and a lamp PSL is lighted when a 75

train is present on the passing siding or turn-out track.

Each of these indicator lamps is first illuminated when a train enters the corresponding track section in the field which indication is initially displayed by a flashing of the corresponding indicator lamp until the operator has acknowledged the presence of the train by pressing the cancelling key CK. The indicator lamp is then steadily illuminated until the train leaves the section. If the train leaves the section prior to the acknowledgment by the operator, the indicator continues flashing until acknowledged.

The two "route" indicators, characteristic of this invention, are preferably small indicating lamps WRL and ERL located adjacent to the track switch, and provided with arrows, or equivalent direction indicating means, which is displayed when the lamp is lighted.

20 The "no route" indicator of this invention is also preferably an indicating lamp NRL, located adjacent the track switch on the track diagram, and having a color distinctive from the other indicating lamps. These various indicating devices are controlled by magnetic stick polar indication relays IR, which are operated by means of the communication system to positions corresponding with the position or condition of the device in the field being indicated. The indication relays IR, IR¹, IR² and IR³ respond to the presence of a train on their corresponding track sections in the field; while relay IR⁴ responds to the east governing signals at clear or stop; relay IR⁵ to the west governing signals at clear or stop; relay IR⁶ to the position of the track switch; and relay IR⁷ to the track switch locked or unlocked.

In the case of those indication relays IR which are associated with track section occupancy indications, as for example relays IR, IR¹, IR² and IR³, a storing relay SR⁰ and an acknowledging stick relay AS are associated therewith in order to provide that the indication originally displayed shall be held over until the operator acknowledges such new indication, although the train may have passed from the associated track section. More specifically, the relay IR¹, controlled in accordance with the east approach track section, together with relays SR¹ and AS¹ are shown as controlling the east approach indicator lamp EAL. 50 In a similar manner, the relays IR, IR² and IR³ with their associated stick and acknowledging relays are employed to control their respective indicator lamps OSL, WAL and PSL, such control being merely indicated for the sake of simplicity in the drawings.

55 A contact 25 is provided to continuously open and close so as to alternately place upon and remove energy from a flashing bus 26. This contact 25 is conventionally shown as operated by a cam member which may be continuously operated by a suitable electric motor. It is to be understood, however, that any other suitable means may be employed for this purpose, such for example as a flashing relay operated only as required.

Two directional stick relays WS and ES are employed for maintaining the route indicating lamps energized, although a train may have passed over the OS track section putting the associated signals to stop, until the operator manually causes the signals to remain at stop.

The control of the indicating means on the control board in accordance with this invention, also involves an out-of-correspondence relay OC⁰.

75 **Field station equipment.**—With reference to the

typical field station shown in Fig. 2, a turn-out track having rails 27 is connected to the main track having rails 28 by means of a track switch TS. The track switch TS is suitably controlled from one extreme locked position to the other by any suitable type switch machine (not shown), such for example as shown in the patent to W. K. Howe, Patent No. 1,466,903, dated September 4, 1923, which switch machine is controlled by a switch machine relay SMR with such control subject to the associated signalling system and suitable approach locking means. The switch machine relay SMR is in turn controlled in accordance with the position of the switch control lever SML in the control office through the medium of the communication system.

The switch machine (not shown), thus remotely controlled by the operator, is preferably provided with a dual control selector, such as disclosed in the patent granted to W. K. Howe, Patent No. 1,852,573 dated April 5, 1932, so that a member of a train crew can locally operate the track switch for local train movements, as desired, after first obtaining permission from the operator by telephone, or the like.

25 A portion of the main track adjacent the track switch TS and the fouling portion of the turn-out track is included in a detector track section having the usual battery and track relay T associated therewith, which section is separated from the rest of the track by the usual insulated joints. East of the detector track section is an east approach track section having its battery and track relay T¹. West of the detector track section is a west approach track section having its battery and track relay T². A track section for the turn-out track is also provided with a track battery and a track relay T³. These track relays besides serving to furnish suitable approach and detector track section protection for the track switch TS, also serve to indicate the presence of trains in the control office through the medium of the communication system.

50 Signals 1 and 1A serve to govern east bound traffic over the track switch TS from the main track or the turn-out track respectively; while signals 2 and 2A serve to govern west bound traffic over the track switch TS on the main track or onto the turn-out track respectively. These signals 1—1A and 2—2A, arranged to control train movements over the track switch TS in the usual way in accordance with recognized practice, are respectively controlled by signal control relays 1F—1AF and 2F—2AF which are selected in accordance with the position of the track switch TS and the direction relay DR; while their energization is dependent upon the relay SR and traffic conditions in accordance with the principles of automatic block signal systems, all in a manner shown and described, for example, in the prior patent of S. N. Wight, Patent No. 2,082,436 dated June 1, 1937. Although these signals have been shown as being of the color light type, it is to be understood, however, that they may be of the semaphore type, or any other suitable type rail-way signal.

55 The relays SMR, SR and DR, which are controlled over the communication system in accordance with the position of the levers SML and SGL, as more specifically pointed out in the above mentioned patent granted to N. D. Preston et al., Patent No. 2,129,183 dated September 6, 1938, are of the polar magnetic stick type, which maintain their contacts in the last energized position as determined by the polarity of the 75

last energization regardless of subsequent de-energization.

The position of the track switch TS is indicated by the usual switch repeating relay WP which is of the polar-neutral type relay energized with a particular polarity in accordance with the position and locked condition of the track switch TS through the usual switch box or point detector mechanism (not shown). The energization of this relay WP is also governed in accordance with the operated condition of the dual selector, when such a mechanism is employed in conjunction with the switch machine.

The signals 1—1A and 2—2A are indicated as being at stop by the energization of the relay M which is controlled through a series of back contacts on the signal control relays 1F—1AF and 2F—2AF. If semaphore signals were employed, the contacts controlling the M relay would be located within the signal mechanisms.

An out of correspondence relay OC is employed to indicate, when energized, that the traffic controlling devices at this location are in correspondence with the controls established by the operator in the control office, as represented at the field station by the relays SMR and SR. A control relay CL is provided to be energized when the field station is receiving controls from the central control office.

Inasmuch as the detector track section, having the track relay T, is comparatively short, a light engine or a short train might easily pass over this section before the communication system, particularly in the case of a station selective type communication system, could transmit indication of the presence of the train upon this section. Thus, a stick relay ST is associated with the track relay T to store its deenergized condition; while also associated therewith is a cancelling relay CR which is energized when the stored condition in the stick relay ST has been transmitted.

As the track sections associated with the relays T¹, T² and T³ are comparatively long, it is considered unnecessary to provide such storing and cancelling means. However, should the conditions of practice require such means, it is obvious that similar means can be associated with each of these relays in a similar manner as provided for the relay T.

A change in track circuit conditions causes the change relay CH to be energized by reason of momentary contacts on the track relays T¹, T², T³ and the storing relay ST; while a change in the conditions of the traffic controlling devices causes the relay GS to be energized by reason of two slow acting relays AX and BX together with suitable circuits.

It is believed that the nature of the invention, its advantages, and characteristic features can be best understood with further description being set forth from the standpoint of operation.

Operation of the system

Before discussing the detail performance and mode of operation in the various steps included in the operation of the system under different conditions and pointing out the circuits involved, it would appear to be expedient to outline briefly the general scheme of operation.

This system is illustrated as operable by use of a communication system of the station selective type as heretofore pointed out. While such a selective type system could be operated continuously, it is preferably arranged to be normally at rest when no controls are to be transmitted

from the control office, or no new indications are to be communicated to the control office. The relays and circuits are shown in the positions assumed when the system is in its normal condition of rest, with the communication system so conditioned that it may be initiated into operation for the transmission of control impulses and/or indication impulses. When thus set into operation, the system goes through what is conveniently termed an operating cycle and then comes to rest again.

During each operating cycle of the system, new controls may be transmitted to any station and new indications may be received either from that station or some other station, and the system continues to go through these operating cycles so long as there are new controls or indications to be transmitted.

The whole operating cycle may be said to be divided into two parts, the first of which is employed for selecting and/or registering the station and the second of which is employed for the actual transmission of the controls and/or indications.

The transmission of controls to a field station is accomplished by first positioning the control levers, or other circuit controllers, and then initiating the system into operation by actuating the associated starting button. This procedure can be varied to suit the particular type communication system employed. For example, in some systems the movement of a control lever is sufficient to initiate the system.

During the station selecting part of the cycle thus initiated, the station selecting relay SO is selectively conditioned in accordance with the code call transmitted. If the station is selected by the continued energization of the relay SO, the transfer relay TR is energized at the end of the station selecting part of the cycle. The system continues to operate for the transmission of controls to the function control relays, such for example as relays SMR, DR and SR, the details of which are immaterial to the present invention. The arrangement illustrated in Fig. 6 shows one method of selectively controlling the SMR relay.

The transmission of indications from a field station may be accomplished by initiation of the system at the field station. If a change in track circuit conditions occurs, the relay CH is energized; while if a change in traffic controlling device conditions occurs, the relay GS is energized. In the event that either of these relays is energized, the system is caused to operate through one complete cycle; while, if both of these relays are energized, the system is caused to operate through two complete cycles.

The energized or deenergized condition of the group selecting relay GS determines what group of indications is to be transmitted for that cycle. If the change relay CH is energized and the group selecting relay GS is deenergized, track circuit indications are transmitted; but, if both relays are energized, indications of the traffic controlling devices are transmitted during that cycle of operation and the track circuit indications are transmitted on a subsequent cycle. This feature is provided by a stick circuit for the relay CH which is closed during the operation of the system while the relay GS is energized. If the relay GS is energized and the relay CH is not energized, the indications associated with the traffic controlling devices are of course transmitted.

During the station selecting or registering part of the operating cycle incurred by initiation from a field station, the station selecting relay SI is selectively conditioned at the particular station 5 corresponding to the resulting code call transmitted to the control office. If the station is selected by the continued energization of the relay SI, the relay TR is energized at the end of the station selecting part of the cycle. The system 10 continues to operate for the transmission of indications from the selected station.

During the station selecting part of a cycle initiated in the field, the resulting code call transmitted to the control office registers the selected 15 station by the energization of the corresponding station relay C³. The relay C³ causes the indication impulses transmitted on the second part of the cycle to be applied to the indication relays IR corresponding to the particular station which 20 has been registered.

Normal conditions.—When there are no trains on the various track sections and the operator has established no routes for the passage of trains, all of the indicator lamps on the track diagram are deenergized, so that the control panel presents a "dark board" to the operator. The announcement of a train at any point is readily apparent by the illumination of the associated indicator lamp after which the operator by suitable positioning of his control levers may establish the desired route for the particular train indicated.

With reference more particularly to Fig. 2 of the accompanying drawings, the track relays T, T¹, T² and T³ are shown normally energized as is usual in common practice.

The signals 1—1A and 2—2A are at stop, as the associated control relays 1F—1AF and 2F—2AF are deenergized by reason of the positions assumed by the contacts of relay SR in correspondence with control lever SGL. With the signals at stop, the relay M is energized through a circuit from (+), through back contacts 30, 31, 32 and 33 of relays 1AF, 1F, 2F and 2AF respectively, wire 34, winding of relay M, to (—).

The track switch TS is in a normal position as last controlled by its switch machine (not shown) by reason of the position assumed by the contacts of relay SMR in correspondence with normal position of the control lever SML.

With the traffic controlling devices in correspondence with the control relays SMR and SR, as they should be under normal conditions, the relay OC is energized through a circuit traced from (+), through back contact 35 of relay SL, wire 36, contact 37 of relay SMR in a right hand position, wire 38, contact 39 of relay WP in a right hand position, wire 40, front contact 41 of relay M, wire 42, contact 43 of relay SR in a right hand position, wire 44, front contact 45 of relay WP, wire 46, back contact 47 of relay CL, wire 48, upper winding of relay OC, to (—).

This energizing circuit for the relay OC is completed only with the communication system at rest, as indicated by the relay SL. However, the relay OC is maintained energized when the system is in operation, through a stick circuit from (+), through front contact 49 of relay OC, wire 50, to contact 37 and thence through the rest of the circuit as above traced. In other words, should the communication system be initiated into operation for the transmission of controls or the transmission of indications, thereby energizing the relay SL at the control office and at each field station, the relay OC would remain

energized through its stick circuit in spite of the opening of back contact 35, if the traffic controlling devices at the station remain in correspondence with the associated control relays.

With reference more particularly to Fig. 1 of the accompanying drawings, the indicating relays IR give indications under normal at rest conditions that correspond to the positions of the control levers, thus the out of correspondence relay OC⁰ is energized through a circuit traced from (+), through polar contact 55 of relay IR⁷ in a right hand position, wire 56, contact 57 of relay IR⁶ in a right hand position, wire 58, control contact 59 of lever SML in a normal position, wires 60 and 61, contact 62 of lever SGL in an intermediate position, wire 63, contact 64 of relay IR⁵ in a right hand position, wire 65, contact 66 of relay IR⁴ in a right hand position, wire 67, winding of relay OC⁰, to (—).

As the track switch TS is in a normal position indicated in the control office by the relay IR⁶ in a normal position, the miniature track switch point ts is actuated to a normal position by means of the normal actuating coils 70 which are energized from (+), through contact 71 of relay IR⁶ in a right hand position, coils 70, to (—).

Transmission and display of track circuit indications.—For convenience let us assume that a train proceeding in a west bound direction enters the east approach track section deenergizing the track relay T¹ (see Fig. 2).

The deenergization of the relay T¹ causes the momentary contact 75, in passing from an energized position to a deenergized position, to momentarily complete a circuit between its associated front and back contacts. This circuit momentarily energizes the change relay CH from (+), through momentary contact 75 of track relay T¹, wires 76, 77 and 78, winding of relay CH, to (—). The change relay CH is thus sufficiently energized to close its front contacts, which completes a stick circuit from (+), through back contact 79 of stepping relay 4, wires 80 and 81, front contact 82 of relay CH, wires 85 and 79, winding of relay CH, to (—). Also in multiple with this stick circuit, positive energy is applied from (+), through back contact 83 of relay SI, to wire 84, and thence through the stick circuit as traced. With the change relay CH maintained energized, the communication system is initiated into operation to transmit indication of the fact that the relay T¹ is deenergized.

The initiation of the communication system into operation energizes the relays SL at the control office and at each of the field stations, after which the step-by-step mechanisms at each location sequentially operate in synchronism. On each of the steps impulses are transmitted in accordance with the code call of the station in order to register this station in the control office and select the station for transmitting indications. The registration of this station in the control office results in the energization of relay C³ while the selection of the field station for transmitting indications is indicated by the energization of relays SI and TR.

After the selection of the field station and its registration in the control office, the step-by-step mechanisms at the control office and at this station continue to operate for the transmission of indication impulses. Thus, for the second part of the cycle, as the step-by-step mechanisms at this field station and at the control office continue to operate in synchronism, including the stepping relays 4, 5, 6, 7 and 8, also the stepping

relays *d*, *e*, *f*, *g* and *h*, local indication circuits are closed at the control office and at the selected field station. On each of the steps the indication circuits at the field station energize or leave deenergized the relay *P* which controls the energized condition of the series message circuit extending from the control office through each of the field stations. This message circuit includes the message relay *M*⁰ in the control office which in turn determines whether negative or positive energy shall be placed upon the indication circuits local to the control office.

As the group selecting relay *GS* is deenergized prior to the initiation of the system into operation and remains deenergized during such operating cycle, for reasons hereinafter pointed out, although some change should occur in the condition of the traffic controlling devices, the indications transmitted for this cycle under consideration are associated with the track circuit conditions adjacent this field station.

On the first indication step, the relay *P* is left deenergized, as the relay *GS* is deenergized with front contact *84* open. Thus, the relay *M*⁰ remains energized and places positive potential on the indication bus *15* during the message period of that step. The relay *GS*⁰ remains deenergized although a circuit is traced from (B+), through front contact *87* of relay *M*⁰, back contact *88* of relay *LR*⁰, front contact *89* of stepping relay *d*, indication bus *15*, wire *99*, front contact *91* of relay *C*³, wire *92*, upper winding of group selecting relay *GS*⁰ to (B+), because the same potential is applied to both of its terminals.

In other words, on this first indication step, the relay *GS*⁰ in the control office is left deenergized or is energized in accordance with the position of the group selecting relay *GS* at the particular field station which is selected. In this case, as the indications to be transmitted are in accordance with track circuit conditions at the field station of Fig. 2, the relay *GS*⁰ remains deenergized in correspondence with the relay *GS*.

Upon the second step, the relay *P* is energized, because of deenergized track relay *T*¹, through a circuit from (+), through back contact *155* of track relay *T*¹, wire *156*, back contact *157* of group selecting relay *GS*, wire *158*, front contact *159* of stepping relay *5*, back contact *143* of stepping relay *4*, front contact *149* of relay *TR*, front contact *150* of relay *SI*, upper winding of relay *P*, to (−). This results in the deenergization of relay *M*⁰ during the message period of that step which places negative potential upon the indicating relay *IR*¹ through a circuit traced from (B−), through back contact *87* of relay *M*⁰, back contact *88* of relay *LR*⁰, back contact *89* of stepping relay *d*, front contact *96* of stepping relay *e*, indication bus *16*, wire *97*, front contact *98* of relay *C*³, wire *99*, back contact *100* of relay *GS*⁰, wire *101*, winding of relay *IR*¹, to center tap *CN* of the battery source.

This actuates the contact *102* of relay *IR*¹ to a left hand position in which the relay *SR*¹ is energized from (+), through contact *102* in a left hand position, wires *103*, *104* and *105*, winding of relay *SR*¹, to (−). The energization of the relay *SR*¹ causes the energization of the east approach indicating lamp *EAL* through a circuit from (+), front contact *106* of relay *SR*¹, wire *107*, indicating lamp *EAL*, wire *108*, back contact *109* of relay *AS*¹, to the flashing bus *26* which is intermittently connected to (−) through contact *25*. Thus, the east approach indicating lamp *EAL* is caused to flash which informs the operator that a train has entered the associated track section in the field.

The indicating lamp *EAL* is insured of continued flashing until the operator actuates the cancelling key *CK*, regardless of the fact that the train might for some reason leave the associated track section. This feature is due to a stick circuit provided for the relay *SR*¹ which is traced from (+), through back contact *112* of relay *AS*¹, front contact *113* of relay *SR*¹, wires *104* and *105*, winding of relay *SR*¹, to (−).

When the operator acknowledges the flashing of indicator lamp *EAL* by depressing the cancelling key *CK*, the acknowledging stick relay *AS*¹ is energized through a circuit traced from (+), back contact *112* of relay *AS*¹, front contact *113* of relay *SR*¹, wires *104* and *114*, winding of relay *AS*¹, wires *115*, *116*, *117*, *118* and *119*, cancelling key *CK* in a depressed position, to (−).

If the train has remained within the track section and is so indicated by relay *IR*¹, a multiple pick-up circuit is provided for relay *AS*¹ from (+), through contact *102* of relay *IR*¹ in a left hand position, wires *103*, *104* and thence through the circuit as traced.

The energization of the relay *AS*¹ is maintained by closure of a stick circuit only if the train has remained upon the track section causing the contact *102* of relay *IR*¹ to remain in a left hand position. This stick circuit may be traced as follows: from (+), through contact *102* of relay *IR*¹ in a left hand position, wires *103*, *104* and *114*, winding of relay *AS*¹, wires *115* and *120*, front contact *121* of relay *AS*¹, to (−).

The energization of the acknowledging stick relay *AS*¹ causes the indicator lamp *EAL* to be continuously energized by placing the continuous negative potential upon the wire *108* through front contact *109*.

However, if the train has left the associated track section and the contact *102* of relay *IR*¹ is in a right hand position, relay *AS*¹ is energized prior to the actual response of its contact and only part way through the operation of the contacts, although the cancelling key *CK* is maintained depressed. This is due to the opening of its own energizing circuit at back contact *112*. The relay *AS*¹ is made slightly slow releasing to give sufficient time for the relay *SR*¹ to drop away, which extinguishes the illuminated indicator lamp *EAL*.

Upon the remaining indication steps, the relay *P* is energized or is left deenergized, in accordance with the positions assumed by relays *T*, *T*² and *T*³, in a similar manner as explained for relay *T*¹. In the case under consideration, these track relays are energized.

Thus, the relay *M*⁰ in the control office remains energized causing positive potential to be placed upon the relays *IR*, *IR*² and *IR*³. The contacts of the indicating relays *IR*, *IR*² and *IR*³ therefore remain in their right hand normal positions, maintaining the indicator lamps *OSL*, *WAL* and *PSL*, respectively deenergized, as they are controlled in a similar manner as indicator lamp *EAL*.

Upon the energization of the stepping relay *4* at the way station, with the relay *SI* energized, positive energy is removed from the stick circuit of the relay *CH* by open back contacts *79* and *83*. Thus, with the relay *CH* deenergized, the system returns to an at rest condition after completing the one cycle of operation.

Indications of traffic controlling devices.—The operator in the control office acknowledges the

presence of the train upon the east approach section by depressing the cancelling key CK which results in a steady illumination of the indicator lamp EAL.

- 5 Assuming that the operator desires to route this train onto the turn-out track, he positions the switch machine lever SML in a reverse dotted line position and moves the lever SGL to a left hand dotted line position, after which he presses 10 the starting button SB. The actuation of the starting button SB causes the communication system to be initiated into operation and to operate through a cycle to transmit the controls established by the levers SML and SGL in a suitable manner to actuate the control relays SMR, SR and DR at the field station into correspondence therewith.

The out of correspondence relay OC⁰ is now deenergized with contact 59 of lever SML in a 20 reverse position out of correspondence with contact 57 of relay IR⁶ which indicates the normal position of the track switch TS. Similarly, with the contact 62 of lever SGL in a right hand west bound controlling position which is out of 25 correspondence with the stop condition of the signals indicated by the indicating relays IR⁴ and IR⁵, the energizing circuit for the relay OC⁰ is further opened. With the relay OC⁰ deenergized, the no route lamp NRL is illuminated by 30 reason of a circuit from (+), through indicating lamp NRL, wire 125, back contact 124 of relay OC⁰, to (-). The illumination of this no route lamp advises the operator that the traffic controlling devices at the corresponding field station 35 have not yet responded to the new positioning of the control levers.

Prior to the operation of the relays SMR, SR and DR, the field station must be selected which is indicated by the energization of the relays SO and TR. This results in the energization of the 40 control relay CL from (+), through front contact 126 of relay TR, wire 127, front contact 128 of relay SO, wire 129, winding of relay CL, to (-).

45 At the field station thus selected (see Fig. 2), the relays SMR, SR and DR assume their new positions so that the out of correspondence relay OC is deenergized by reason of contact 37 of relay SMR being in a left hand dotted line position out of correspondence with the contact 39 of relay WP. Similarly, the circuit of the relay OC is opened by reason of the contact 43 of relay SR being in a left hand dotted line position out 50 of correspondence with the contact 41 of relay M.

The traffic controlling apparatus, including the track switch TS and the signal 2A, is operated in 55 response to the controls transmitted to the relays SMR, SR and DR in accordance with the block signalling system and approach locking means associated therewith, in a manner set forth for example in the above mentioned patent to S. N. Wight, Patent No. 2,082,436 dated June 1, 1937.

However, no indications are transmitted to the control office as the relay GS is not energized until the traffic controlling devices are operated into correspondence with their respective control relays. The only indication which might be desirable to be known by the operator is the fact that the track switch TS is in midstroke, which 65 fact he may assume to be true inasmuch as the no route lamp NRL is still illuminated. If the operator desires an actual indication of the condition of the track switch, he may cause the system to repeat or check the indications as specifically pointed out hereinafter.

After this cycle of operation of the communication system, which transmits the controls to the control relays SMR, SR and DR, is completed, the relay CL is again deenergized. But during that cycle of operation, after the energization of relay CL and the deenergization of relay OC, the relay AX is energized from (+), through back contact 49 of relay OC, wire 130, winding of relay AX, to (-), so that the deenergization of the relay CL at the completion of the cycle does not 10 actuate the relay GS.

Considering that the track switch TS is operated to a reverse locked position which is repeated by the relay WP, and that the signal 2A is cleared with relay 2AF energized which deenergizes relay M, the energizing circuit for the relay OC is closed. This energizing circuit for the relay OC, which is completed after the traffic controlling devices are in correspondence with their control relays, is completed only when the 15 communication system is at rest, because the energization of the relay OC completes a momentary pick-up circuit for the relay GS, later explained, which relay GS can not be energized during a cycle of operation as the transmission 20 of track circuit indications might be erroneously interrupted. More specifically, this circuit is traced from (+), through back contact 35 of relay SL, wire 36, contact 37 of relay SMR in a left hand dotted line position, wire 131, contact 39 of relay WP in a left hand dotted line position, wire 40, back contact 41 of relay M, wire 132, contact 43 of relay SR in a left hand dotted line position, wire 44, front contact 45 of relay WP, wire 46, back contact 47 of relay CL, wire 48, 35 upper winding of relay OC, to (-).

The energization of the relay OC closes its stick circuit at front contact 49, and opens the energizing circuit of the relay AX at back contact 49, but the relay AX is sufficiently slow acting to permit a momentary pick-up circuit to be completed for the relay GS. This momentary pick-up circuit for the group selecting relay GS is traced from (+), through front contact 135 of relay OC, wire 136, front contact 137 of relay AX, wires 138 and 139, upper winding of relay GS, to (-). This momentary energization of the relay GS actuates its contacts to energized positions closing a stick circuit from (+), through back contacts 142 and 143 in multiple of the 40 relays SI and TR respectively, wire 145, front contact 146 of relay GS, lower winding of relay GS, to (-).

The energization of the relay GS initiates the 45 communication system into operation for the registration and the selection of this station. The operation of the system causes relays SL⁰ and SL to be energized. At the end of the station selecting part of the cycle, the station registering relay C³ is energized in the control office, 50 and the relays SI and TR are energized at the field station.

The relay GS is maintained energized through the cycle of operation by the completion of another stick circuit by the relay SI prior to the 55 energization of the relays SI and TR. This stick circuit for the relay GS is traced from (+), through front contact 35 of relay SL, wires 140, 141 and 145, front contact 146 of relay GS, lower winding of relay GS, to (-).

Upon the first indicating step of this cycle of 60 operation, the relay P is energized from (+), through front contact 84 of relay GS, wire 147, front contact 148 of relay 4, front contact 149 of relay TR, front contact 150 of relay SI, upper 65 70 75

- winding of relay P, to (-). This results in the deenergization of the relay M⁰, which places negative potential upon the relay GS⁰ by back contact 87 through a circuit as heretofore traced.
- 5 As opposite potentials are in this case applied to the opposite terminals of the upper winding of the relay GS⁰, its contacts are actuated to energized positions closing a stick circuit for the relay GS⁰ from (+), through lower winding of 10 relay GS⁰, front contact 151, wire 152, front contact 153 of relay SL⁰, to (-).
- Upon the next step, the relay P is energized in accordance with the position of the polar contacts of relay WP. As the track switch TS is in a reverse position and the polar contacts of the relay WP are in left hand dotted line positions, the relay P is energized from (+), through contact 161 of relay WP in a left hand dotted line position, wire 162, front contact 157 of relay GS, wire 15
- 20 158, front contact 159 of stepping relay 5, back contact 148 of stepping relay 4, front contact 149 of relay TR, front contact 150 of relay SI, upper winding of relay P, to (-). Thus the relay M⁰ is deenergized, thereby placing negative potential 25 upon the indicating relay IR⁶. This energizing circuit for the relay IR⁶ is traced from (B-), through back contact 87 of relay M⁰, back contact 88 of relay LR⁰, back contact 89 of relay d, front contact 96 of relay e, indication bus 16, wire 97, front contact 98 of relay C³, wire 99, front contact 100 of relay GS⁰, wire 164, winding of relay IR⁶, to (CN). The application of negative potential to the relay IR⁶ causes its contacts to be actuated to left hand dotted line positions.
- 30 35 The actuation of contact 71 to a left hand dotted line position energizes the coils 154 from (+), contact 71 in a left hand dotted line position, coils 154, to (-). This energization of coils 154 causes the miniature track switch point ts to be actuated to a reverse position.
- 40 Upon the next step, the relay P remains deenergized by reason of the open back contact 166 of relay WP, as the relay WP is energized in accordance with the reversed and locked condition 45 of the track switch TS. Thus, relay M⁰ remains energized and places positive potential upon the relay IR⁷ through a circuit traced from (B+), front contact 87 of relay M⁰, back contact 88 of relay LR⁰, back contacts 89 and 96 of stepping 50 relays d and e respectively, front contact 167 of stepping relay f, indication bus 17, wire 168, front contact 169 of relay C³, wire 170, front contact 171 of group selecting relay GS⁰, wire 172, winding of relay IR⁷, to the center tap of the battery source indicated as (CN). The polar contact 55 of the relay IR⁷ therefore remains in a right hand normal position.
- Upon the next step, the relay P remains deenergized as both of the signal control relays 1AF and 1F are deenergized. Thus, the relay M⁰ remains energized placing positive potential on the indicating relay IR⁴ through a circuit from 60 (B+), through front contact 87 of relay M⁰, back contact 88 of relay LR⁰, back contacts 89, 96 65 and 167 of stepping relays d, e and f, front contact 173 of stepping relay g, indication bus 18, wire 174, front contact 175 of relay C³, wire 176, front contact 177 of relay GS⁰, wire 178, winding of relay IR⁴, to the center tap of the battery source indicated as (CN). The polar contacts of 70 the relay IR⁴ therefore remain in right hand normal positions.
- Upon the next step, the relay P is energized by reason of the energized condition of the signal control relay 2AF through a circuit traced 75
- from (+), through front contact 180 of relay 2AF, wire 181, front contact 182 of relay GS, wire 183, front contact 184 of stepping relay 8, back contacts 185, 186, 159 and 148 of stepping relays 7, 6, 5 and 4 respectively, front contact 149 of relay TR, front contact 150 of relay SI, upper winding of relay P, to (-). Thus, the relay M⁰ is deenergized placing negative potential upon the relay IR⁵ through a circuit traced from (B-), through back contact 87 of relay M⁰, back contact 88 of relay LR⁰, back contacts 89, 96, 167 and 173 of stepping relays d, e, f and g respectively, front contact 190 of stepping relay h, indication bus 19, wire 191, front contact 192 of relay C³, wire 193, front contact 194 of relay GS⁰, wire 195, winding of relay IR⁵, to the center tap of the battery source indicated as (CN). The polar contacts of the relay IR⁵ are therefore operated to left hand dotted line positions.
- The actuation of the polar contacts of relay IR⁵ to left hand dotted line positions completes the last indication which is necessary to indicate that the traffic controlling devices at the field station are in correspondence with their respective control levers upon the control panel. The relay OC⁰ is now energized through a circuit traced from (+), through polar contact 55 of relay IR⁷ in a right hand position, wire 56, polar contact 57 of relay IR⁶ in a left hand position, wire 196, contact 59 of lever SML in a reverse position, wires 60 and 61, contact 62 of lever SGL in a west controlling position, wire 198, contact 64 of relay IR⁵ in a left hand dotted line position, wire 65, contact 66 of relay IR⁴ in a right hand position, wire 67, winding of relay OC⁰, to (-). The energization of the relay OC⁰ opens the energizing circuit of the no route lamp NRL at back contact 124.
- The energization of the out of correspondence relay OC⁰ completes the pick-up circuit for the west stick relay WS from (+), through contact 55 of relay IR⁷ in a right hand position, wire 56, contact 57 of relay IR⁶ in a left hand position, wire 196, contact 59 of relay SML in a reverse position, wires 60, 199 and 200, winding of relay 40 WS, wires 201 and 202, contact 203 of indicating relay IR⁵, wires 204 and 205, front contact 124 of relay OC⁰, to (-). The energization of the relay WS completes the energizing circuit for the west route lamp WRL from (+), through front contact 206 of relay WS, wire 207, indicator lamp WRL, to (-).
- The completion of the cycle is indicated by the deenergization of the relays SL at the control office and at each of the way stations. The deenergization of the relay SL⁰ (see Fig. 1) opens the stick circuit of the relay GS⁰ at front contact 153; similarly, the deenergization of the relay SL (see Fig. 2) opens the stick circuit of the relay GS at front contact 35, as the contacts 50 of relays SI and TR are still in energized positions.
- The operator now has the resultant route information displayed before him on the control panel. Immediately he notes the illumination of the west route lamp WRL and the presence of a train on the east approach by illumination of lamp EAL, as all other indications, associated with this track switch, are extinguished. The routing of the train may be further verified by 60 noting the position of the miniature track switch ts.
- The indicators on the control panel, associated with other controlled points, are also extinguished unless similar conditions have been established. 75

Priority of traffic controlling device indications.—Let us assume that the train on the east approach track section accepts the clear signal 2A and proceeds onto the detector track section, 5 over the track switch TS, and onto the turn out track.

The occupancy of the detector track section de-energizes the track relay T which energizes the 10 storing relay ST from (+), through back contact 216 of relay T, wires 217 and 218, winding of relay ST, to (-). This relay is maintained energized through a stick circuit from (+), through back contact 219 of cancelling relay CR, wire 220, front contact 221 of relay ST, wires 222 and 218, 15 winding of relay ST, to (-). The energization of the relay ST actuates a momentary contact 223 thereby energizing the change relay CH in a similar manner as explained in connection with the track relay T¹.

20 The deenergization of the track relay T also causes the signal control relay 2AF to be deenergized through the medium of the signalling system associated therewith. This deenergization of the relay 2AF causes the energizing circuit of the 25 relay M to be closed at back contact 33. When the contact 41 of relay M thus assumes an energized position, the pick-up circuit and one stick circuit for the relay OC is opened at back contact 41, which deenergizes this relay OC consider- 30 ing the communication system to be at rest, to be transmitting controls to this or some other station, or to be transmitting indications from some other station. If the system is transmitting indications from this station (for example track 35 circuit indications) then the relay SI is energized and the relay OC is maintained energized through a stick circuit from (+), through front contact 35 of relay SL, wire 140, front contact 142 of relay SI, wire 224, front contact 225 of relay 40 OC, lower winding of relay OC, to (-).

Assuming that the relay OC can be deenergized, an energizing circuit is completed for the group 45 selecting relay GS during the interval of time required by the slow acting relay AX to be energized through back contact 49 of relay OC. This momentary circuit is traced from (+), through back contact 135 of relay OC, wire 226, back contact 228 of relay CL, wire 229, back contact 137 of relay AX, wires 138 and 139, upper winding 50 of the relay GS, to (-). The relay GS is maintained energized through its stick circuits as heretofore pointed out.

Assuming that the relays CH and GS become 55 energized simultaneously, the communication system is initiated into operation by both relays simultaneously; but if the relays are energized at different times, the first relay becoming energized will effect the initiation of the system into operation.

60 Under normal operation the change relay CH and the group selecting relay GS are energized prior to the selection of the station for the transmission of the associated indications. With the relay GS energized it is evident that the indications associated with the traffic controlling devices at this station are transmitted first. Therefore, an additional stick circuit for the relay CH is closed with the relay GS energized, in order 65 that the system will again be initiated into operation for the transmission of the new track circuit indications standing ready for transmission. This holding stick circuit for the relay CH is traced from (+), through front contact 230 of 70 relay GS, wires 231, 80 and 81, front contact 82, 75

of relay CH, wires 85 and 78, winding of relay CH, to (-).

With the relay GS energized and the communication system initiated into operation, indication impulses are transmitted in the usual manner as 5 heretofore explained. During this particular cycle of operation, the new indication transmitted is the one related with the signal control relay 2AF which is now deenergized. Thus, the indicating relay IR⁵ receives positive potential operating 10 its contacts to right hand positions. The energizing circuit for the relay OC⁰ is thereby opened causing its back contact 124 to complete the circuit for the no route lamp NRL.

However, the west route lamp WRL is main- 15 tained energized by the west stick relay WS, which relay is maintained energized through a stick circuit from (+), through contact 55 of relay IR⁷ in a right hand position, wire 56, contact 57 of relay IR⁶ in a left hand dotted line 20 position, wire 196, contact 59 of lever SML in a reverse position, wires 60, 199 and 200, winding of relay WS, wires 201 and 210, front contact 211 of relay WS, wire 213, contact 214 of lever SGL in a west controlling position, to (-).

The relay WS is thus maintained energized so long as the track switch TS is indicated as being in correspondence with the control lever SML, and the signal control lever SGL remains in its last operated position, regardless of the fact that 30 a train may pass beyond the signal thereby putting that signal at stop which causes the corresponding indicating relay to indicate an at stop position. In other words, although the train moves onto the OS track section, in this case 35 causing the signal 2A to go to stop, which through the medium of the communication system causes the contacts of the indicating relay IR⁵ to be returned to right hand positions, the west stick relay WS is maintained energized. This maintains the west route lamp WRL illuminated telling the operator that the route will be clear for subsequent train movements, although the no route lamp NRL is energized telling the operator that the signals are now at stop.

The relay GS is deenergized at the end of the 40 operating cycle upon the deenergization of the relay SL, but the system is again initiated into operation due to the failure of the relay CH to be deenergized upon the first indicating step (relay 45 50 energized) with relay GS energized. The operating cycle, thus initiated, is executed with the relay GS deenergized, thereby permitting the transmission of the track circuit indications.

During this cycle of operation, the system functions in a similar manner as above described for the transmission of track circuit indications. In other words, the track relays T¹ and T govern the relay P upon their respective steps so as to control the polar contacts of the indicating relays 55 IR¹ and IR respectively to left hand positions; while the track relays T² and T³ govern the relay P upon their respective steps so as to control the polar contacts of relays IR² and IR³ respectively to right hand positions. This control of 60 the relay by the track relays is similar as explained for the track relay T¹, except in those cases where storing means is associated therewith, as in the case of track relay T.

For example, the relay P is controlled upon 70 its respective step by the relay ST through a circuit from (+), through front contact 232 of relay ST, upper winding of cancelling relay CR, wire 233, back contact 234 of relay GS, wire 235, front contact 186 of stepping relay 6, back con- 75

tacts 159 and 148 of stepping relays 5 and 4 respectively, front contact 149 of relay TR, front contact 150 of relay SI, upper winding of relay P, to (-). The contacts (not shown) of the indicating relay IR are operated in accordance therewith to left hand positions.

The energization of the cancelling relay CR opens the stick circuit of the relay ST, thereby deenergizing the relay ST, if the detector track section is not occupied; but if the section is still occupied with the track relay T deenergized, then the relay ST will remain energized, so that a stick circuit is completed for the relay CR from (+), through front contact 232 of relay ST, lower winding of relay CR, front contact 236 of the relay CR, to (-). This cancelling relay CR is maintained energized until the relay ST is deenergized by the picking up of the track relay T. In other words, if the relay CR were not energized after the transmission of the associated indication, the relay ST would remain energized although the track relay T became picked up.

Thus, the relays ST and CR provide means for storing the occupancy of the detector track section only until the communication system has operated to transmit the associated indication impulses. In a like manner, similar storing and cancelling relays could be employed with the track relays T¹, T² and T³ for accomplishing the same purpose with respect to the indications associated therewith.

The relay IR has associated therewith relays SR⁰ and AS for controlling the indicator lamp OSL in a similar manner as explained for indicator lamp EAL. With the contacts of relay IR in left hand positions, circuits are closed to thereby illuminate the OS indicating lamp OSL, which indication will be a flashing one until the operator actuates the cancelling key CK.

At the completion of this cycle of operation, the communication part of the system returns to an at rest condition, as the change relay CH is deenergized upon the energization of the first stepping relay as heretofore pointed out.

The train continues over the track switch TS onto the turn out track thereby deenergizing the track relay T³. Indication of this fact is transmitted to the control office in the manner which will be understood by analogy to the above description. This results in the illumination of the indicator lamp PSL, which gives a flashing indication until the operator actuates the cancelling key CK.

It is to be understood, that the transmission of the track circuit conditions has been explained for the entrance of the train only, but that similar transmission of track circuit indications occurs upon the departure of the train from each track section, that is, the change relay CH is also energized by the momentary contacts upon the energization of the respective track relays. This results in the return of the polar contacts of the corresponding indicating relay IR to right hand positions extinguishing the corresponding indicator lamps.

As long as the operator leaves the signal control lever SGL in either extreme position for clearing east or west bound signals, trains may follow each other with spacing provided by the automatic block signal system, provided of course that the particular signal, which is cleared thereby, is not what is termed a "stick signal" sometimes employed in certain cases. Each time a train passes and puts the cleared signal at stop, the no route lamp will be illuminated until the

train passes beyond the governing track sections allowing the signal to again clear. If the particular signal cleared is a stick signal, it will remain at stop until the operator returns his control lever to a cleared position for such signal to clear. In such a case, the no route lamp will remain illuminated until the operator moves his control lever SGL to the stop position, after which the operation is similar to that already explained.

The functioning of the system has thus been described as including operation of the system in response to movement of control levers for the transmission of controls, together with the operation of the system resulting from the passage of a train through territory under the control of the operator. Although other combinations of train moves can be made, and other combinations of track lay outs may be controlled by such a system, it is to be understood that the particular example chosen was selected merely for making clear the most usual functions and features of the invention rather than the total number of combinations of operations which might occur in practice.

Operator may check indications.—Let us assume that the system is in a normal condition, as shown in the accompanying drawings, and that the operator desires for one reason or another to check the positions of the traffic controlling devices at the field station.

To do this, it is only necessary for the operator to initiate the system into operation by actuation of the starting button SB without the movement of any control lever. The operation of the communication system is thereby initiated for the selection of the associated field station, which selection is determined by the energization of the corresponding relays SO and TR. The energization of these relays results in the energization of the control relay CL which de-energizes the out of correspondence relay OC at back contact 41 of relay CL.

The deenergization of the relay OC energizes the slow acting relay AX, so that upon completion of the cycle of operation initiated from the control office, the relay CL is deenergized, again completing the circuit for the relay OC. During the time required for the slow acting relay AX to assume a deenergized position, after such energization of relay OC, a circuit is completed for momentarily energizing the relay GS to thereby cause the system to be initiated for the transmission of the controlled device indications from that field station. This pick-up circuit for the relay GS is traced from (+), through front contact 135 of relay OC, wire 136, front contact 137 of relay AX, wires 138 and 139, upper winding of relay GS, to (-). With the relay GS energized the system is initiated for the transmission of indications.

In other words, this arrangement just pointed out provides that the operator may check the controlled device indications even though they are actually in correspondence with the control levers.

The system is also provided with means to enable the operator to check the controlled device indications of a field station, although the controlled devices are not in correspondence with their respective control levers.

Let us assume that the operator moves the signal control lever SGL to a clear position for one direction or the other, which results in the control of contact 43 of relay SR to a left hand

position (see Fig. 2), and the deenergization of relay OC. If the proper signal does not clear, due to the presence of a train or some other reason, the relay M will remain energized and the relay OC will not be energized subsequent to the control transmitted to relay SR.

The operator notes that the no route lamp NRL remains illuminated and desires to check the indications to see if it is a failure of the system to transmit or an actual condition at the field station. He actuates the starting button SB to select the corresponding station.

With the relays SO and TR energized after the selection of the station, the relay CL is energized. However, prior to the selection of the station, with the relays CL and OC deenergized, the slow acting relay BX is energized from (+), through back contact 240 of relay CL, wire 241, winding of relay BX, wire 242, back contact 243 of relay OC, to (-). Thus, as soon as the relay CL is energized, a circuit is completed for energizing the relay GS during the time that the slow acting relay BX is assuming its deenergized position. This momentary energizing circuit for the relay GS is traced from (+), through front contact 240 of relay CL, wire 244, front contact 245 of relay BX, wires 246 and 139, upper winding of relay GS, to (-). The energization of the relay GS initiates the system into operation for the transmission of indications associated with the control devices, in a manner similar to that heretofore pointed out.

In other words, the system is provided with means for the operator to cause the controlled devices to transmit their indications regardless of whether they are in correspondence or whether they are out of correspondence with their associated control levers, without in any way changing the route conditions, by suitably causing the selection of the associated field station.

Summary.—The centralized traffic control system herein shown and described as one embodiment of the present invention, provides information of the condition of the controlled devices and the presence of trains in a clear, concise and accurate manner.

In accomplishing this purpose, the present invention provides means for organizing and properly relating the indications with the controlled devices and the control machine, and also provides means for storing individual indications and certain groups of indications in order to insure their transmission and reduce the total number of operating cycles.

The invention also points out the advantages of grouping indications into groups that are of distinctive classes in that their transmission may be separated by several cycles of operation without impairing the facility of the system. However, it is to be noted in this connection, that although the grouping feature and the feature of storing or suppressing controlled device indications have been shown combined, it must be understood, they may be employed separately and still remain within the scope of the invention.

The system further provides that the operator may check the positions of the controlled devices at a field station, without either changing their positions or providing additional control steps, by means of selecting the station with or without the transmission of controls thereto.

Having thus shown and described a centralized traffic control system for railroads as one specific embodiment of the present invention, it is de-

sired to be understood that this form is selected to facilitate in the disclosure of the invention rather than to limit the number of forms which it may assume; and, it is to be further understood that various modifications, adaptations and alterations may be applied to the specific form shown to meet the requirements of practice, without in any manner departing from the spirit or scope of the present invention except as limited by the appended claims.

Having described my invention, I now claim:

1. In a centralized traffic controlling system, a railroad track switch, a detector track section associated with said switch, a synchronous selector type communication system connecting said track switch to a central control office, means for causing a plurality of indications to be transmitted over said communication system during a single cycle of operations and means causing indications of the condition of said track switch and said track section to be transmitted over said communication system during different cycles of operation, whereby the length of each cycle of operation is reduced.

2. In a centralized traffic controlling system, a control office, a railroad track switch, signals governing traffic over said switch, annunciator track sections associated with said track switch, a synchronous selector type communication system connecting said track switch to said control office and automatically controlled for transmitting a plurality of indications during each cycle of operation, and means for automatically transmitting during any particular operating cycle of said synchronous selector communication system either the indications of said track switch and signals only or the indications of the conditions of said annunciator track sections only.

3. In a centralized traffic controlling system, a control office, a plurality of field stations, step-by-step means in the control office and at each field station operated synchronously, a message circuit extending from the control office to the several field stations, conditioning means at each field station for controlling the energization of said message circuit in accordance with a distinctive code call for that station, means in the control office responsive to the respective conditions of said message circuit for registering the particular station having the most superior code call, and means at each station for determining which group of a plurality of groups of indications are to be transmitted after the corresponding station has been registered in said control office.

4. In a centralized traffic controlling system, a control office, a plurality of field stations, step-by-step means in the control office and at each field station operated synchronously, a message circuit extending from the control office to the several field stations, station selecting means in part located at the control office and in part at each field station for determining the particular station which may employ said message circuit during a particular system of operation, a plurality of traffic controlling devices, a plurality of track sections, route indicating means actuated in accordance with the condition of said plurality of traffic controlling devices, annunciator indicating means actuated in accordance with the occupancy of said plurality of track sections, and means selectively causing said plurality of traffic controlling devices to transmit indications during a particular operating cycle in preference to said plurality of track sections when both are

70
75
75

ready to transmit indications at the beginning of a cycle of operation.

5. In a centralized traffic controlling system for railroads, a control office, a field station, a selective type communication system operable through cycles of operation for transmitting impulses from said field station to said control office, a plurality of traffic governing devices at said field station, a plurality of indication storing relays at said control office corresponding to said traffic governing devices, means causing different groups of said traffic governing devices to transmit impulses in accordance with their condition to their respective indication storing relays on separate operating cycles when said traffic governing devices assume new conditions, and means determining the sequence in which the various groups may transmit impulses on succeeding cycles of operation.
- 20 6. In a centralized traffic controlling system, a control office, a field station, a communication system connecting said control office to said field station, a plurality of traffic controlling devices at said field station, control means in said control office for transmitting controls to any one or several of said traffic controlling devices, and indication means at said field station for automatically transmitting indications to said control office of the condition of said traffic controlling devices at that field station each time any one or several of said traffic controlling devices changes its condition in response to a control only when the changed conditions of all of such devices correspond respectively to the controls transmitted to such devices.
- 40 7. In a centralized traffic controlling system, a control office, a plurality of field stations, a communication system connecting said control office to each of said field stations, a plurality of traffic controlling devices at each of said field stations, control means in said control office for transmitting control impulses to their respective traffic controlling devices, indication means at each field station for automatically transmitting indication impulses to the control office of the condition of said traffic controlling devices when said devices have completed their operation into correspondence with their respective control means, and means manually operable for causing said indication means to transmit indication impulses of the condition of said traffic controlling devices independently of their condition with respect to their respective control means.
- 55 8. In a centralized traffic controlling system, a railroad track switch, signals indicating clear or stop for governing traffic over said switch in one direction, switch control means for governing operation of said track switch, signal control means for governing operation of said signals, a route indicator lamp for said one direction, means for illuminating said indicator lamp when said switch is in correspondence with said switch control means and said signals indicate clear in correspondence with said signal control means, and means maintaining said indicator lamp illuminated, when said signals are caused to indicate stop due to traffic conditions, until said signal control means is operated into correspondence with said signals to stop.
- 70 9. In a centralized traffic control system for railroads, a control office, a plurality of field stations, a step-by-step mechanism in the control office and at each field station operated synchronously, control and message circuits extending to each field station, a plurality of traffic

controlling devices at each field station, control means at the control office for transmitting control impulses over said control circuit to said traffic controlling devices, transmitting means at each field station for transmitting indication impulses over said message circuit to said control office in accordance with the condition of said traffic controlling devices for each change in the condition of said devices, and means preventing operation of said transmitting means when the condition of said traffic controlling devices is changed in response to said control impulses said means being effective only until all of said plurality of devices have responded to their respective control impulses.

10 10. In a centralized traffic control system for railroads, a plurality of manually controlled devices said devices being controlled successively through the medium of a selector type system, and means indicating the condition of said devices through the medium of said selector type communication system only if said devices have all responded to their respective manual control.

15 11. In a centralized traffic control system for railroads; a control office; a field station; a communication system interconnecting said control office and said field station; a plurality of traffic controlling devices at said field station; control means at said field station for operating each of said traffic controlling devices, said control means being manually governed from said control office through the medium of said communication system; indication transmitting means for transmitting indications of the condition of said traffic controlling devices to said control office, said indication transmitting means including means for causing indications to be transmitted only after all said traffic controlling devices are operated by their respective control means into correspondence therewith; and means for causing indications to be transmitted irrespective of the correspondence between said control means and their respective traffic controlling devices only after said control means are manually governed in the same manner twice in succession.

20 12. In a centralized traffic control system for railroads, a control office, a plurality of field stations, a plurality of traffic governing devices at each of said field stations, a communication system for selectively transmitting control impulses to said traffic governing devices at a particular field station during each operation when initiated from the control office and for selectively transmitting indication impulses to said control office in accordance with the condition of said traffic governing devices at a particular field station during each operation when initiated from that field station, manually operable means for initiating said system from the control office for the transmission of control impulses to a particular field station, and means for initiating said system from a particular field station for the transmission of indication impulses to the control office from that field station only after that field station has received the same control impulses during a second operation.

25 13. In a centralized traffic control system for railroads, a railroad track switch, signals capable of displaying proceed or stop indications for governing traffic over said switch in one direction, switch control means for governing operation of said track switch, signal control means for governing operation of said signals, switch indication means for indicating the position of said track switch, signal indicating means for indicating means for indicating

cating whether said signals are displaying proceed or stop indications, a directional stick route relay, a pick-up circuit for said directional stick route relay closed only when said switch control means 5 and said switch indication means are in correspondence with said signal control means in a condition for causing said signals to display a proceed indication and said signal indicating means to indicate such proceed condition of said 10 signals, a stick circuit for said directional stick route relay closed only when said switch control means and said switch indication means are in correspondence with said signal control means still remaining in its previous condition as set up 15 for causing said signals to indicate proceed, and an indicator controlled by said route relay.

14. In a centralized traffic control system for railroads; a control office; a plurality of field stations; a plurality of traffic controlling devices at 20 each field station; control levers in the control office for each of said traffic controlling devices; a selective type communication system connecting said control office with said field stations; means for transmitting controls in accordance 25 with said control levers to said traffic controlling devices at each station, one station at a time; and means at each station for transmitting indications of the condition of the traffic controlling devices at each field station to the control office 30 only after all said traffic controlling devices have responded to said controls, said means including means for transmitting indications irrespective of the response of said traffic controlling devices if the same controls are transmitted twice to the 35 same traffic controlling devices at a particular station.

15. In a centralized traffic controlling system, a railroad track switch, a switch machine for operating said track switch, signals for governing 40 traffic over said track switch, a switch control lever for governing operation of said switch machine, a signal control lever for governing operation of said signals, a route lamp for indicating when said track switch is in correspondence 45 with said switch control lever and said signals are in correspondence with said signal control lever, and an additional lamp for indicating when either said track switch or said signals are out of correspondence with their respective levers.

16. In a centralized traffic controlling system, a railroad track switch, a detector track section associated with said switch, a synchronous selector type communication system connecting said track switch to a central control office, means for 55 causing a plurality of indications to be transmitted over said communication system during a single cycle of operations, means causing said indications of the condition of said track switch and said track section to be transmitted over 60 said communication system during different cycles of operation whereby the length of each cycle of operation is reduced, and means responsive to a condition requiring the transmission of both track switch and track section indications for causing said system to transmit said track switch indications first.

17. In a system of centralized traffic control for railroads, a control panel in the central office having thereon a track diagram representing the 70 portion of the railroad under control, a manually movable switch control lever and an indicator associated with each track switch on the diagram, a code type communication system for governing the operation of the several switches in accordance with the position of their respective control 75

levers and also transmitting to the central office indications reflecting the normal position, the reverse position and the unlocked condition of said respective switches, indicating means in the control office responsive to the switch indications thus transmitted, and means for displaying the indicator associated with each switch lever whenever that lever is in a position out of correspondence with the last indicated position of the corresponding switch and whenever said unlocked condition of said switch is transmitted.

18. In a centralized traffic control system for controlling the operation of a power operated track switch from a central office and for indicating in said central office the position and locked condition of said switch, the combination with indicating means responsive to the position and locked condition of the track switch, of a manually operable lever for controlling said switch, and an indicator associated with said lever and controlled jointly by said lever and said indicating means so as to be displayed whenever said lever is in a position out of correspondence with the position of the track switch or whenever the track switch is unlocked.

19. In a centralized traffic control system, the combination with a communication system of the multiple impulse type, of a power-operated track switch, a manually movable lever in the central office for governing the operation of said communication system to control the operation of said track switch, indicating means responsive during the operation of said communication system to the position and locked condition of said track switch, and an indicator associated with said lever and controlled jointly by said lever and said indicating means, said indicator being displayed whenever said lever is in a position out of correspondence with the last indicated position of the track switch manifested by said indicating means or whenever said indicating means is in a condition corresponding with the unlocked condition of the track switch.

20. A control panel for centralized traffic control systems comprising, a track diagram, a manually movable lever for each power-operated track switch, an out-of-correspondence lamp for each switch lever, and means for always steadily lighting any particular one of said lamps whenever the corresponding track switch is unlocked or is in a locked position out of correspondence with the position of the associated switch lever.

21. In a remote control system of the character described, the combination with a power-operated track switch at a field location, of a control panel at a control office including a switch control lever for governing the operation of said track switch and a movable miniature switch point and an indicator associated with said lever on the control panel in the control office, an indicating means in the central office automatically operated over line wires in accordance with the position of the track switch in the field, said indicating means automatically operating the miniature switch point, and means for illuminating said indicator jointly controlled by said indicating means and said switch control lever, said indicator being illuminated whenever the position of the track switch in the field manifested by said indicating means does not match the position of said control lever.

22. In a centralized traffic control system, a power-operated track switch, a control lever in a central office, a miniature switch point at the central office, indicating means in the central

- office automatically responsive to the position and locked condition of said track switch, means controlled by said indicating means for operating said miniature switch point to a position corresponding with said track switch, and an indicating lamp lighted whenever said indicating means shows that the track switch in the field is in a position out of correspondence with the position of said control lever, or is unlocked.
- 5 23. In a system of centralized traffic control for railroads, a control panel in the control office having thereon a track diagram representing the track layout with miniature switch points representing the track switches, manually operable levers on said control panel for governing the operation of the switches and signals associated with the track layout, an out-of-correspondence lamp associated with each miniature switch point on the control panel, indication means in the control office for indicating the position and locked condition of each of the track switches in the field, and means controlled jointly by said indication means and said control levers for lighting a particular one of said out-of-correspondence lamps whenever the position of the corresponding track switch, as manifested by said indication means, is out of correspondence with the control set up for that track switch by said levers, said means also lighting a particular one of said out-of-correspondence lamps whenever said indication means indicates the unlocked condition of that track switch.
- 10 24. In a remote control system for railroads, a track switch having a normal closed position and a reverse closed position, control means operable from a remote point for moving said switch from one closed position to the other, indication means responsive to each change in position of said switch for indicating at said remote point whether the switch is closed or open, and means rendered effective when said control means is operated for preventing the transmission to said remote point of the open indication of said switch provided the switch is opened in response to the operation of said control means.
- 15 25. In a remote control system for railroads, a track switch having a normal closed position and a reverse closed position, control means operable from a remote point for moving said switch from one closed position to the other, indication means responsive to each change in position of said switch for indicating at said remote point whether the switch is closed or open, means rendered effective when said control means is operated for delaying the transmission to said remote point of an indication of the position of the switch until the switch completes its movement in response to the operation of the control means provided the switch is closed when the control means is operated, and for causing an immediate transmission of an open indication of the switch provided the switch is open when the control means is operated.
- 20 26. In a remote control system for railroads, a track switch having a normal closed position and a reverse closed position, control means operable from a remote point for moving said switch from one closed position to the other, indication means responsive to each change in position of said switch for indicating at said remote point whether the switch is closed or open, means rendered effective when said control means is operated for causing the indication means at said remote point to be controlled when the switch completes its movement in response to the opera-
- 25 tion of the control means provided the switch is closed when the control means is operated, and to cause the indication means to indicate that the switch is open only when the switch has been opened prior to said operation of the control means.
- 30 27. In a centralized traffic control system for railroads, a control office and a field station, a normally-at-rest multiple impulse code type communication system connecting the control office and field station, a plurality of traffic controlling devices at the field station, control relay means at the field station for each of said traffic controlling devices for controlling the operation of such devices, manually governed means at the control office for initiating said communication system and transmitting control impulses to said control relay means through the medium of said communication system, means at the field station for transmitting indication impulses to said control office through the medium of said communication system in accordance with the condition of said traffic controlling devices when the communication system is initiated into operation, and means requiring all of said traffic controlling devices to operate into correspondence with their respective control relay means for initiating said system into operation to transmit indication impulses.
- 35 28. In a centralized traffic control system for railroads, a normally-at-rest code type communication system connecting a control office and a field station, a plurality of traffic controlling devices at the field station, a control relay at the field station for each of said traffic controlling devices for governing its operation, means at the field station causing said control relays to be responsive to control codes transmitted over said communication system, means at the control office for initiating and transmitting control codes over said communication system, means at the field station for transmitting indication codes over said communication system in accordance with the conditions of the several traffic controlling devices when said communication system is initiated into operation at the field station, means for initiating said communication system into operation at the field station, said means requiring all of said traffic controlling devices to operate into correspondence with their respective control relays, and means for initiating said communication system into operation when any one or all of said devices operates out of correspondence with its respective control relay.
- 40 29. In a centralized traffic control system for railroads, a normally-at-rest code type communication system connecting a control office and a field station, a plurality of traffic controlling devices at the field station, a control relay at the field station for each of said traffic controlling devices for governing its operation, means at the field station causing said control relays to be responsive to control codes transmitted over said communication system, means at the control office for initiating and transmitting control codes over said communication system, means at the field station for transmitting indication codes over said communication system in accordance with the conditions of the several traffic controlling devices when said communication system is initiated into operation at the field station, a correspondence relay controlled by said traffic controlling devices and their control relays so as to indicate when all of said devices are in correspondence with their control relays and when any one or all

of said devices are out of correspondence, and means for initiating said communication system into operation when said correspondence relay shifts from one position to the other except when such shift is due to a disruption of correspondence between said traffic controlling devices and their control relays upon the reception of a control code by said control relays.

30. In a system for controlling traffic on railroads, a communication system extending between a control office and a field station for transmitting control codes from the control office to the field station and for transmitting indication codes from the field station to the control office, means at the control office for transmitting control codes over said communication system, control relays at the field station responsive to the control codes transmitted over said communication system, a plurality of traffic controlling devices at the field station controlled by said control relays, means at the field station effective when initiated into operation for transmitting indication codes to the control office through the medium of said communication system in accordance with the condition of the several traffic controlling devices, a correspondence relay, circuit means for energizing said correspondence relay when there is correspondence between all of said traffic controlling devices and their control relays 30 and for deenergizing said correspondence relay when there is a lack of correspondence between said traffic controlling devices and their control relays, said circuit means preventing a change in the energized or deenergized condition of said correspondence relay while indication codes are being transmitted, and circuit means for initiating said indication transmitting means into operation upon the energization or deenergization of said correspondence relay.

40 31. In a centralized traffic controlling system of the type described, a power-operated track switch at a remote field station, a switch control means located at a central office, two indication relays at the central office for indicating the normal and reverse positions of said track switch and also the unlocked or mid-stroke position of such track switch, a multiple impulse code type communication system connecting the central office and field station for rendering said power-operated track switch controllable by said switch control means at the central office and for controlling said indication relays in accordance with the normal and reverse positions and the unlocked or mid-stroke position of said track switch, and indication means controlled jointly by said indication relays and said switch control means for in-

dicating when said track switch is out of correspondence with said switch control means or when said track switch is unlocked.

32. In a centralized traffic controlling system for railroads; a power-operated track switch at a remote field station; a control panel in the central office having a miniature track switch located thereon; a switch control lever located on said control panel; an indicator lamp associated on the panel with said switch control lever; two indication relays at the central office, one for indicating the normal and reverse positions of said track switch, and the other for indicating the locked or unlocked condition of such track switch; a multiple impulse code type communication system connecting the central office and field station for rendering said power-operated track switch controllable by said switch control lever and for controlling said one of said indication relays in accordance with the normal and reverse position of said track switch and the other of said indication relays in accordance with the locked and unlocked condition of said track switch; electro-responsive means controlled by said one indication relay for operating said miniature track switch; and circuit means controlled jointly by said indication relays and said switch control lever for causing said indicator lamp to be illuminated whenever said switch control lever is out of correspondence with the position of the track switch as manifested by said one indicating relay and also to be illuminated whenever such track switch is unlocked as manifested by said another indicating relay.

33. In a centralized traffic controlling system, a railroad track switch, a switch machine for operating said track switch, signals indicating clear or stop for governing traffic over said track switch, a switch control lever for governing operation of said switch machine, a signal control lever for governing operation of said signals to clear or stop conditions, switch indication means controlled in accordance with the position of said track switch, signal indication means controlled in accordance with the clear or stop condition of said signals, a route indicator lamp, and circuit means for energizing said route indicator lamp only when said switch indication means is in correspondence with said switch control lever and only when said signal indication means is in correspondence with said signal control lever, said circuit means including contacts operated by said switch and signal control levers respectively and contacts operated by said switch and signal indication means respectively.

NEIL D. PRESTON.

DISCLAIMER

2,139,562.—*Neil D. Preston*, Rochester, N. Y. CENTRALIZED TRAFFIC CONTROLLING SYSTEM. Patent dated December 6, 1938. Disclaimer filed May 18, 1940, by the assignee, *General Railway Signal Company*.

Hereby enters this disclaimer as to claims 7 and 12 of said Letters Patent: and hereby disclaims from claims 1, 2, 4, and 16 any system for centralized traffic indication, except wherein during each and every indication cycle of operation of the system either indications of the conditions of "traffic controlling devices" (switches and/or signals) only and exclusive of indications of the occupancy of "track sections", or indications of the occupancy of "track sections" only and exclusive of indications of the conditions of "traffic controlling devices" can be transmitted; and hereby disclaims from claim 5 any system for centralized traffic indication, except wherein during each and every indication cycle the "group of traffic governing devices" the indications of which devices are transmitted include either indications of conditions of track switches and/or signals only and exclusive of indications of the occupancy of track sections, or indications of the occupancy of track sections only and exclusive of indications of the conditions of switches and signals.
